UNITED STATES PATENT OFFICE.

WILLIAM W. BAYS, OF CHARLOTTE, NORTH CAROLINA.

WASHING-MACHINE.

1,193,348.

Specification of Letters Patent. Patented Aug. 1, 1916.

Application filed April 6, 1916. Serial No. 89,488.

To all whom it may concern:

Be it known that I, WILLIAM W. BAYS, a citizen of the United States, residing at Charlotte, in the county of Mecklenburg and State of North Carolina, have invented certain new and useful Improvements in Washing-Machines; and I do declare the following to be a full, clear, and exact description of the invention, such as will enable others skilled in the art to which it appertains to make and use the same.

This invention relates to improvements in washing machines of that type known as clothes pounders.

The principal object of the invention is to provide a simply constructed device of this character, which will be very efficient in operation and can be very inexpensively manufactured.

As is common in devices of this character, the clothes are cleaned by forcing the water and air contained in the pounder through the same. This is accomplished in the present device by the several air chambers from which the air and water rushes and intensely agitates the water around the clothes.

With the above and many other objects in view, my invention resides in the novel features of construction, combination and arrangement of parts which will be herein-after more particularly described and claimed.

In the accompanying drawing:—Figure 1 represents a central vertical longitudinal section through the washing machine. Fig. 2 is a bottom plan view thereof. Fig. 3 is a detail horizontal section on the line 3—3 of Fig. 1 showing a portion of the device in plan view.

Referring more particularly to the drawing, the numeral 1 designates an outer cone-shaped casing having a flat top 2 which is slightly concaved and provided with a plurality of openings 3. A conical shaped cap member 4 is secured to the top 2 at its lower edge and covers the openings 3, thus forming an air chamber 5, which will be herein-after more particularly described. The top 2 is slightly depressed or concaved to permit any water entering the chamber 5 to readily drain therefrom through the openings 3.

Depending from the inner wall of the outer cone 1 is a funnel shaped member 6, said member being preferably soldered or

otherwise secured thereto at the junction of the top 2 with said member 1. It will be noted that the lower edge of the funnel shaped member 6 extends downwardly to a point about one third the distance between the top 2 and the lower edge of the cone 1 and has secured thereto an inner cone 7 through which water passes into the member 6 when the device is in operation. A plurality of large outlet openings 8 are formed around its upper portion, through which the water entering said member passes into a chamber 9 formed by the cone 1 and a conical shaped member 10 which is secured at its lower edge to the lower edge of said cone and at its upper edge to the funnel shaped member 6. The point of attachment of the upper edge of the member 10 to the funnel shaped member 6 is spaced inwardly from the openings 8 as illustrated. This cavity or chamber 9 it will be seen is substantially wedge shaped in cross section and the water which enters the same through the openings 8 is expelled through the smaller openings 11 formed through the cone 1 adjacent its lower edge. Any water, however, which is trapped within the cavity when the device is no longer in operation is permitted to flow therefrom through the small discharge apertures 12 formed at the intersection of the lower edges of the cone 1 and the member 10. A portion of the water which enters the cavity 9 passes through the plurality of openings 13 formed in the conical shaped member 10 adjacent its upper edge into an additional chamber 14. This last mentioned chamber is formed by the wall of the member 10, an annular band 15, and a horizontal partition 16. The band 15 is connected at its lower edge to the lower edge of the inner cone 7 and its upper edge to the funnel shaped member 6 intermediate the ends thereof. The horizontal partition is secured to this band 15 and to the inner wall of the member 10 and has a plurality of large outlet openings 17 formed therein through which the water from the chamber 14 is expelled. Water also enters the chamber 14 by way of the chamber 18, it passing into the same through the openings 19, and out through the openings 20. Since the openings 19 are spaced from the bottom of the chamber 18, drainage openings 21 are formed at the junction of the band 15 and the inner cone 7 to permit the escape of water when the device is

not in operation. The inner cone at its lower end is provided with the crossed strips 22 which prevent the clothes being washed from entering the funnel shaped member 6. 5 An additional feature of the invention is the provision of the ring 23 which is secured by its upper edge to the conical shaped member 10 adjacent the lower edge thereof, its lower edge being free and spaced from the edge to the cone 1. As the device is forced down through the water and the clothes, the water entering the space between this ring and the member 10 escapes with considerable force through the openings 24 which are formed entirely around the same adjacent its connection with said member 10.

As a means for operating the parts heretofore described, I provide a pair of parallel handles 25 connected at their upper ends by the cross bar 26. These handles may be of any desired length and are attached to the cone 1 by means of the sockets 27 whose lower ends are soldered to said cone on opposite sides thereof. Any preferred means may be employed for holding the handles within the sockets the means employed in the present instance being set screws 28, thus permitting said handles to be readily removed. Any water which enters the sockets may readily escape through the drainage openings 29 formed in the lower ends thereof. The upper portions of the sockets are supported by the braces 30 which connect 35 the same with the cap member 4. This cap member is also provided with a socket member 31 formed by a cylinder which extends through the top thereof and into the chamber 5 where it is secured. This is provided 40 so that an additional form of handle may be used if desired. In other words the parallel handles 25 may be removed and a single handle inserted in the socket 31.

The operation of this device is similar to 45 those of similar nature, it being moved up and down in the tub of water containing the clothes. As the pounder is moved downwardly the air contained therein is compressed to a considerable extent and is 50 forced upwardly into the chamber 5 and the upper portion of the chamber 9. The water enters the inner cone and passes upwardly into the funnel shaped member from where it passes into the chamber 9. Some water 55 also enters said chamber through the openings 11, but since the openings 8 are considerably larger than the other openings, this water is forced backwardly through said openings 11 together with the water 60 which enters through the openings 8 and causes considerable agitation in the water adjacent the outside of the device. At the same time the water which enters the chamber formed by the ring 23 is forced 65 through the openings 24 therein and also

stirs up the water so that the clothes may be washed. The water within the device is further agitated by that passing through the cavities or chambers 14 and 18.

From the foregoing description taken in connection with the accompanying drawing, it will be obvious that I have invented a much improved clothes washing device which will effectively clean the clothes by forcing combined air and water through the same, and that because of the peculiar arrangement of the air chambers the washing will be greatly facilitated. By providing the large chamber 5 the device may be readily lifted from the bottom of the tub 80 due to the expansion of the compressed air therein which greatly aids in overcoming the suction which would otherwise result.

I claim as my invention:

1. In a device of the class described, a 85 conical shaped member, a funnel shaped member secured to the upper edge thereof, an inner cone secured at its upper edge to the lower edge of said funnel shaped member, an annular band secured to the funnel 90 shaped member by one edge and at its other edge to the inner cone, said band having a plurality of inlet openings adjacent its bottom and a plurality of outlet openings adjacent its upper edge, and a handle for operating 95 said device.

2. In a device of the class described, a conical shaped member, a funnel shaped member secured to the upper edge thereof, an inner cone secured at its upper edge to 100 the lower edge of said funnel shaped member, an annular band secured to the funnel shaped member at one edge and at its other edge to the inner cone, said band having a plurality of inlet openings adjacent its bottom and a plurality of outlet openings adjacent 105 its upper edge, a horizontal partition connecting said conical shaped member and said band to form a chamber, said partition having a plurality of outlet openings, and a handle for operating said device.

3. In a device of the class described, an outer cone, a funnel shaped member depending from the inner wall thereof and having a plurality of openings adjacent its 115 outer edge, a conical shaped member secured by its lower edge to the lower edge of said cone, its other edge being secured to said funnel shaped member at a point spaced inwardly from said openings to form a chamber, said chamber having a plurality of outlet openings to permit the escape of water entering through the other openings, an inner cone secured at its upper edge to the lower edge of said funnel shaped member, 120 an annular band secured to the funnel shaped member at one edge and at its other edge to the inner cone, said band having a plurality of inlet openings adjacent its bottom and a plurality of outlet openings ad- 125

jacent its upper edge, a horizontal partition connecting the said conical shaped member and said band to form a chamber, said partition having a plurality of outlet openings, 5 said conical shaped member also having a plurality of apertures opening into said last mentioned chamber, and a handle for operating said device.

In testimony whereof I have hereunto set my hand in presence of two subscribing wit- 10 nesses.

WILLIAM W. BAYS.
